CHRISTIAN BECKER, OF ROCKFORD, ILLINOIS, ASSIGNOR TO MATTISON MACHINE WORKS, OF ROCKFORD, ILLINOIS, A CORPORATION OF ILLINOIS.

SANDING DRUM.

Application filed January 13, 1926. Serial No. 80,875.

This invention relates generally to sanding drums and in particular to sheet clamping and tensioning structure associated therewith.

5 It is customary in providing sanding drums with a sheet of abrasive paper to place a layer of padding such as felt between the drum and the paper. In use, the continued action of the rotating drum on the work causes the 10 layer of felt to stretch and loosen circumferentially of the drum. The abrasive sheet also stretches in a similar manner because of the paper stretching and also because of the decrease in thickness of the stretched felt, 15 considerable slack is produced in the paper wound on the drum. The present invention aims to provide automatic and independent tensioning means for the padding and for the paper in order to maintain substantially 20 uniform conditions of tension throughout the use of the drum. Not only is the tension equalized throughout the use of the drum, but the felt is prevented from bunching up under the paper to make the sanding roll 25 eccentric.

Another object of the invention is to provide a paper tensioning device which pulls upon the paper substantially tangentially of the drum.

30 Still another object of the invention is the provision of spring operated tensioning devices and of cam means for releasing and positively holding said devices.

Another object is to so relate a sheet clamping means and a sheet tensioning means that one is automatically rendered inoperative when the other is made inoperative.

Still another object is to provide sheet holding devices which can be duplicated at 40 intervals along an elongated drum with a common means for rendering said duplicate structures inoperative.

Still other and ancillary objects and advantages of the invention will be apparent 45 from the following description of an illustrative and exemplary embodiment of the invention as shown in the accompanying drawings in which:

Figure 1 is a longitudinal cross section of 50 a sanding drum, partly in elevation.

Fig. 2 is a transverse section along the line 2—2 of Fig. 1.

Fig. 3 is a transverse section along the line 3—3 of Fig. 1.

Fig. 4 is a plan view in section along the 55 line 4—4 of Fig. 2.

Fig. 5 is a detailed view of the paper tensioning device.

Although the following description refers in detail to the structure illustrated in the 60 drawings, it is to be understood that the invention is not to be construed as limited to the construction herein disclosed and described. To the mind of one skilled in the art, other arrangements of the parts and 65 other embodiments of the invention will doubtlessly occur and such constructions and arrangements are herein contemplated by the invention as expressed in the appended claims.

70 In the drawings there is shown a device comprising a longitudinally split cylindrical drum which may have any desired length. According to its length it has a sufficient 75 number of duplicate structures or groups of such structures which serve to fasten and tension a padding placed over the drum surface and a sheet of abrasive material placed over said padding. The ends of the padding and of the abrasive sheet are preferably 80 secured within the periphery of the drum and enter through the longitudinal gap provided therein. The advancing ends of the abrasive sheet and the padding sheet are fixedly 85 secured to the drum while the tail ends may also be secured, there being employed means to keep the padding and the paper always 90 taut irrespective of the stretching, creeping or loosening of the sheets as the drum is used.

It is obvious that there is tendency for the 95 paper or padding to stretch or creep toward the tail end as the sheet moves relatively to the work and consequently tensioning devices are preferably positioned to operate on the tail ends of the padding and the paper.

A drum 10 is indicated which is preferably made of cast iron, being constructed with transverse webs 11 spaced apart within the drum and provided with supporting bearings 12 for a mounting shaft 13. Screws 14 hold the drum rigid to the shaft. The drum has an open seam or longitudinal gap 15 defined at one side by an edge 16 of the drum body and on the other side by a cast iron structure

17 substantially triangular and prismatic in shape. This structure is a removable section of the drum and has an arcuate surface 18 forming a section of the drum periphery, and 5 has also an inwardly directed face or flange 19 recessed as shown at 20. The drum section 17 is secured to the drum proper by screws 21 entering the webs 11.

The section 17 is preferably made to provide the advancing edge of the gap 15, the drum being rotated in the direction of the arrow. There is secured to the flange 19, a sheet of padding such as felt 22 and a sheet of abrasive paper 23 outside of the padding. 10 The padding is secured by a screwed cleat or strip 24 clamping it to a ledge 25 formed in the flange 19. The free end of the felt after passing around the drum again enters the gap 15 and passes over the edge 16 where it is secured by means later to be described. The paper strip 23 is similarly placed over the entire drum, but both edges are held against an abutment provided by the flange 19 by a clamping bar 26 which enters the recess 20. 15 Thus the abrasive paper spans the gap from the edge 16 to the flange 19, the spanning portion of the paper being inwardly directed at a slight angle to a tangent of the drum periphery.

20 To enable one to replace the paper readily the clamping bar 26 is mounted for actuation away from the recess by a simple mechanical structure. In Fig. 2 the bar 26 is shown mounted on an arm 27 of a lever having other 25 arms 28 and 29 and turning on a pivot shaft 30 extending parallel to the axis of the drum. A heavy spring 31 is interposed between the arm 28 and the drum 10 to hold the bar 26 tightly in the recess 20. The arm 29 crosses 30 a rock shaft 32 parallel to the shaft 30 and mounted in the webs 11. The shaft 32 has a cam surface acting on the arm 29 to move the lever. The cam surface is formed by flattening the shaft substantially to a semi-circular 35 cross section as shown at 33. The shaft 32 has a squared end 34 to which a suitable wrench or key may be applied for turning the shaft to unclamp the paper, the cam 33 holding the device in an inoperative non-clamping position.

40 As above mentioned the rotation of the drum stretches the felt so that its tail end creeps rearwardly of the drum. A clamping and tensioning means for the tail end of the 45 felt is also contained inside the drum. The clamping means for the felt is made movable and serves not only to hold the felt against the drum but also to move with it as it creeps and thereby to keep it under an even tension 50 as it is elongated in use. The tail end of the felt is folded under the drum edge 16 which is preferably made rounded to minimize the friction thereon. On the underside of the edge 16 the felt is clamped by a movable bar 55 35 having saw-like gripping teeth 36. The

bar 35 is carried on an arm 37 of a lever having other arms 38 and 39 and turning on a shaft 40 paralleling the axis of the drum. A spring 41 is interposed between the arm 38 and the drum 10 to force the bar 35 in a direction to pull the felt taut. The arm 39 crosses a cam shaft 42 having a flattened cam surface 43 and a squared end 44 similar to the other shaft 32.

50 As the paper stretches or loosens in use and as the padding decreases in thickness when it stretches, there is thus produced considerable increasing slack in the paper which should be taken up. It is highly desirable that the slack be taken up with as little friction as possible. For this reason it is pulled substantially in a line deviating but slightly from a tangent to the cylindrical surface. Thus there is avoided considerable pressure and friction at the edge 16. Such pressure 55 also would act to bind the felt more tightly to the edge and hinder its tensioning means from taking up the felt slack.

55 Much of the structure heretofore described has been utilized in providing a tensioning means for the paper. Referring to Fig. 5 the initial position of the paper is shown as a dotted line, the paper spanning the gap from the edge 16 to the recess 20 at a slight angle to the tangent. A paper tensioning 60 bar 45 lies beneath the paper and when operative is urged, in the present instance, towards the periphery and across the gap by spring means thus to keep the paper taut as the slack is produced. The paper tensioning bar 45 is carried by a web shaped arm 46 of a lever having other arms 47 and 48 and turning on the above named shaft 30. A spring 49 is placed between the arm 47 and the drum 10 to exert a tensioning force on the paper. The tensioning bar 45 swings about the shaft 30 from the dotted line position of Fig. 5 through the full line operative position shown in Fig. 3, and may move to the limiting position shown in full lines in Fig. 5. The paper tensioning means is thus normally pressed against the paper by its spring 49. As a means to render inoperative the tension bar and to hold it in an out-of-the-way position for replacing the abrasive sheet, a cam is provided to act upon the arm 48. The arm is positioned so that a flat spot 50 formed as a cam on the shaft 40 pivoting the felt tensioning lever serves this purpose. Consequently the pivot shaft 40 is rotatably mounted in bearings along the webs 11 and is provided with a squared end 51.

65 The cylindrical portion of the drum diametrically opposite the gap 15 is constructed relatively thick as indicated at 52 to counterbalance the weight of the holding and tensioning structures. The inner surface of this portion is made flat so that an additional balancing weight 53 may be secured thereto to perfect the balance for high speed operation.

Referring to Figure 1 it will be seen that a long drum may have a plurality of duplicate structures or groups of structures arranged as desired in duplicate groups similar to the group above described in detail. The various cam shafts 30, 40 and 42 therefore preferably extend the whole length of the drum so that they are common to each of the duplicate devices, thus permitting all similar devices 10 to be operated simultaneously from one end of the drum.

In preparing to use the drum one places the padding about the drum, first securing the leading end to the ledge 25 by the clamping cleat 24. The free or tail end of the felt is passed around the drum and is turned under the edge 16 of the drum at a time when the cam shaft 42 is turned opposite to the position shown in Fig. 3 in order to rotate the felt tensioning bar 35 counter-clockwise into an out-of-the-way inoperative position. After placing the felt around the edge 16 the cam shaft 42 is turned into the position shown in Fig. 3 and the spring 41 forces the teeth 36 of the felt tensioning bar 35 into engagement with the felt to pull it taut as the felt slackens through usage. When operative, the spring 41 compels the bar 35 to move clockwise and to take up the slack as it is produced.

In placing the abrasive paper upon the roll the paper clamping bar 26 is first moved into an out-of-the-way non-clamping position by rotating the cam shaft 32. This bar 35 automatically carries the paper tensioning arm 46 with it in case it has not been otherwise moved into its out of the way position by rotating its cam shaft 40. The two free ends of the paper are placed in the recess 20 of the flange 19 and the cam shaft 32 is turned into the position shown in Fig. 2 thus causing the spring 31 to force the paper clamping bar 26 into the recess to clamp the two ends of the paper. The paper is normally placed in the device so that the paper spans the gap as shown in Fig. 5 in dotted lines. If the cam shaft 40 has been turned to hold the tensioning bar 45 in inoperative position it should then be turned a half revolution to permit the spring 49 to exert its pressure to bring the parts into tensioning position shown in Fig. 3. However, it is to be observed that the operation of the paper tensioning means by the controlling cam shaft 50 40 is not necessary since the arrangement of the arm 46 in contiguity with the paper clamping bar 26 causes it to be moved forwardly and rearwardly thereby upon operation of the control shaft 32 of the paper clamping lever. It will be observed by reference to Fig. 1 that the paper tensioning bar 45 terminates at the point indicated at 55 so that in the successive groups of devices the paper tensioning bars function independently. The end of the adjacent tensioning

bar is indicated by the numeral 56. The provision of separate tension bars is not necessary, but it is desirable since it is likely that the sheet at one end of the drum may stretch more than at the other, and this arrangement 70 serves to permit any one section to operate independently of the other sections. Further reference to Fig. 1, however, shows that the felt clamping bar 35 is continuous throughout the length of the drum. The 75 paper clamping bar 26 is likewise continuous. But it is to be understood that these may be separated into independent bars similar to the tensioning bars if such an arrangement is preferred.

It will thus be seen that the invention provides suitable clamping and tensioning structures for sanding drums which can be used singly for small drums or arranged in groups 80 for long drums, and which may be operated 85 by common means from one end of the drum.

I claim as my invention:

1. In a sanding drum comprising a hollow split cylinder, an automatic padding take up and tensioning device comprising, in combination, a lever pivoted to move in a plane transverse to the axis of the drum, a bar carried by said lever and arranged to claw a sheet of padding entering the gap in the cylinder, and a spring acting on said lever 90 to draw the padding around the cylinder.

2. In a sanding drum comprising a hollow split cylinder, a padding take up and tensioning device comprising, in combination, a lever pivoted to move in a plane transverse 100 to the axis of the drum, a bar carried by said lever and arranged to take up a sheet of padding entering the gap in the cylinder by placing a yieldable tensioning draw thereon, a spring acting on said lever so to tension 105 and draw the padding, and cam means operable to move said lever into an inoperative position.

3. In a split-surfaced sanding drum, a holding and tensioning device for an abrasive sheet comprising, in combination, a clamping lever and a tensioning lever, each being freely movable transversely to the axis of the drum, spring means operable on each lever, a clamping bar carried by one of said 110 levers, an abutment in the drum against which the spring operated lever presses the clamping bar to clamp the edges of the abrasive sheet causing a portion of the sheet to span the gap in the cylinder, a tensioning bar 115 carried by the other lever and arranged to be forced across the gap to tension the spanning sheet, the tensioning lever being arranged to be moved against its spring by the clamping bar on unclamping the paper, and means to move the clamping lever to unclamp 120 the paper and to hold the clamping lever positively in non-clamping position whereby said tensioning lever is moved into an inoperative 125 position by the clamping bar.

4. In a sanding drum of the character described adapted to have a sheet of padding between an abrasive sheet and the drum, means to secure one end of the padding sheet, and automatic slack taking up and tensioning means for the other end of the sheet.

5. In a sanding drum of the character described adapted to have a sheet of padding between an abrasive sheet and the drum, means to secure one end of each sheet to the drum, automatic means to take up the slack in the padding sheet after passing around the drum, and other means to tension the abrasive sheet after passing around the drum.

10 6. In a sanding drum comprising a hollow split cylinder, a sheet of padding secured at one end within the cylinder along one side of the slot, and means for clawing the padding

along its opposite edge and maintaining a yieldable tensioning draw thereon around the 20 cylinder.

7. In a sanding drum of the character described having a longitudinal slot therein and adapted to have a sheet of padding between an abrasive sheet and the drum, the ends of which sheet extend into said slot, means to secure one end of each sheet to the drum, means to take up the slack in the padding sheet after passing around the drum arranged to draw the end of the sheet back around one edge of the slot, and other means to tension the abrasive sheet in a direction substantially tangentially of the drum and across the slot.

15 In testimony whereof, I have hereunto affixed my signature.

CHRISTIAN BECKER.
